UNITED STATES PATENT OFFICE.

CHARLES H. STEPHENSON AND GEORGE R. PEAR, OF LYNN, MASSACHUSETTS; SARAH SLADE PEAR ADMINISTRATRIX OF SAID GEORGE RICHARD PEAR, DECEASED.

APPARATUS FOR BENDING WIRED SHEET METAL.

1,073,077.

Specification of Letters Patent.

Patented Sept. 9, 1913.

Application filed June 24, 1910. Serial No. 568,746.

To all whom it may concern:

Be it known that we, CHARLES H. STEPHENSON and GEORGE R. PEAR, of Lynn, in the county of Essex and State of Massachusetts, have invented certain new and useful Improvements in Apparatus for Bending Wired Sheet Metal, of which the following is a specification.

This invention relates to the production 10 of reinforced sheet metal, especially where two different pieces of sheet metal are joined, such as in the manufacture of sheet iron or steel receptacles, as, for instance, ash cans, garbage receptacles and waste pails.

15 A strong and durable sheet metal receptacle is formed with a cylindrical body having its upper edge rolled around a reinforcing wire, and having its lower edge interlocked by rolling with the edge of a down-turned flange of a circular bottom, the two 20 interrolled edges being reinforced by a wire.

Our present invention relates particularly 25 to the apparatus whereby the cylindrical body and the circular bottom are joined and reinforced.

One of the objects of the present invention is to provide an improved apparatus for forming and assembling the cylindrical body and a flanged base member, without 30 unduly crimping the rolled edges during the manufacture.

Another object of the invention is to provide improved apparatus which will enable 35 the cylindrical body portion and the circular flanged bottom member to be conveniently reinforced and interlocked.

To these ends the invention consists in the apparatus substantially as hereinafter described and claimed.

40 Of the accompanying drawings,—Figure 1 is an elevation of the machine in one of its embodiments, looking from the direction toward which the sheet moves when being curved. Fig. 2 is an end view from the 45 right of Fig. 1. Fig. 3 is a fragmentary elevation of the feed rolls and their sleeves, and showing a sheet in section between the rolls and sleeves. Fig. 4 is a detail elevation of one of the sleeves. Fig. 5 is a detail elevation, partly in section, of another sleeve. Fig. 6 is a detail section on line 6—6 of 50 Fig. 3, the section being taken through an upper sleeve at one end of the machine and a lower sleeve at the other end of the machine. Fig. 7 is a perspective view of a

sheet of metal with a flexible mandrel in the position which it may occupy when the sheet is being curved or bent in the direction of the arrow. Fig. 8 represents a section on line 8—8 of Fig. 1, on a larger scale, 60 a sheet of metal and a wire in place being shown between the sleeves. Fig. 9 is a detail elevation of the bracket and guiding rolls shown in Fig. 1, and illustrating the 65 operation of the small rolls on the work. Figs. 10, 11, 12, 13 and 14, are detail sectional views illustrating different steps of the method. Fig. 15 is a view similar to Fig. 11, but illustrating a modification of the structure of the flexible mandrel which 70 may be employed.

Similar reference characters indicate the same or similar parts in all of the views.

Parts of the frame of the bending machine are shown at 15, said parts having the 75 usual slots for the bearing blocks of the elongated feeding rolls 16, 17, and the bending roll 18, all three of these rolls having elongated peripheral portions which are parallel from end to end to act on the body 80 of the sheet, the edge of which is to be wired. Secured to the shaft of the lower feeding roll 17 are a gear 19 and a pinion 20, and to the shaft of the upper feeding roll 16 is secured a pinion 21. Communicating gearing 22, 23, mesh respectively with the pinions 21 and 20. A driving pinion 24, having a crank 25, meshes with the gear 19. By means of the crank 25, the feeding rolls are actuated in the ordinary manner 85 of sheet metal bending machines.

So far as we are aware, it was usually customary, prior to our invention, to form the grooves which permit the passage of wired or folded edges of the sheet metal to pass 95 through, in integral portions of the feeding rolls themselves. Owing to the fact that the roll has a lesser diameter at the bottom of the groove than the rest of the roll, there was an objectionable amount of wear in 100 use, because of the differential surface speed of these portions of the rolls. And if the sheet is wired at both edges, and said edges are not exactly parallel, there would be a serious binding of the edges, as the sheet is 105 carried through in the path indicated by the dotted line in Fig. 2. To overcome these objections, we construct those portions of the rolls which act upon the edges of the sheet, as loose sleeves which are capable of slight 110

longitudinal movement along the shafts of the rolls, as well as the rotative movement thereon. As shown in the drawings, the roll 17 has a sleeve 26 at one end, said sleeve 5 having a plurality of annular grooves. And the bending roll 18 is provided with a similarly formed loose sleeve 27. The upper feeding roll 16, at the same end of the machine, is provided with a loose sleeve 28, 10 which may be flat, because, as shown in Fig. 3, the edge of the sheet which passes between the sleeves 26 and 28 is turned downwardly. At the other end of the machine, the upper feeding roll 16 is provided with a 15 loose sleeve 29, which has a single wide groove. Said roll, as shown in Fig. 5, is formed with a reduced hub portion, on which is adjustably secured, as by screws, a collar 30. By adjusting the collar 30, the 20 width of the groove 31 may be varied. Loosely mounted on the shafts of the bending roll 18, and the lower feeding roll 17, are loose sleeves 32, 33, which may be flat (that is, having no grooves), because the 25 edge of the sheet at that end of the machine is turned upwardly.

It will now be understood that when a sheet of metal *a*, one edge of which has been previously provided with a wire reinforce 30 *b*, and the other edge formed with a flange or lip *c*, with a mandrel or wire of some kind inclosed therein is passed through the machine in the direction of the arrow *x*, in Fig. 7, so as to be curved, the flange or 35 lip *c* would be liable to be crimped down too closely around the wire or mandrel *d*. Since, as will be presently described, it is necessary in later operations to remove whatever was inclosed below the lip *c*, to 40 prevent too close a bend, it is desirable that the edge of the flange or lip *c* shall not be closed downwardly beyond a position of parallelism with the sheet *a*. This is because, if the lip or flange *c* is folded in too 45 far, it must be then pried out or opened to get the mandrel out, and such prying out or opening detracts from the strength and the appearance of the reinforced edge of the finished article. Either one of several 50 devices may be employed to prevent the too close bending of the flange or lip *c*. As shown in Figs. 3, 6, 7 and 11, a wire mandrel *d* is employed, and a flexible mandrel 34, such as a flat chain, is placed against 55 the wire *d*. This flexible mandrel 34 not only holds the wire mandrel *d* closely in the bottom of the bend, but its upper surface supports the edge of the flange or lip *c*, so that the wire *d* and flexible mandrel 34 60 may be readily slipped out after the sheet has been curved, leaving said sheet with a smooth lip or flange, as indicated in Fig. 12.

Instead of employing the wire mandrel *d*, one side of the flexible mandrel itself may 65 be round, as shown at 34^a, in Fig. 15, this

being accomplished by simply making the links along one side of the chain semi-circular in cross-section.

A bracket 36 attached to the frame 15, is provided with two rolls 35 and 37, the roll 35 being removable. The roll 37 bears upon the outer surface of the bend of the sheet metal so as to iron or smooth the same out as the sheet passes through, the action of said roll being best illustrated in Fig. 9. 70 As has been stated, the roll 35 is removable. When a flexible mandrel, such as the chain 34, is employed, the roll 35 is removed. But for some purposes, we find that the roll 35, when in place, as shown in Fig. 9, will serve 75 to so hold the wire mandrel *d* as to provide for giving the proper curvature along the rolled edge, the upper surface of the roll 35 preventing excessive downward bending of the flange or lip *c*. 80

One method of operation is as follows:— A sheet of metal *a* having one edge already wired, as at *b* (see Figs. 3, 7, and 10) is passed through the machine so that the feeding rolls will operate upon the main width of 90 the sheet, the wired edge *b* passing along the grooves of the sleeves 26 and 27, the other edge being received in the groove 31 of the sleeve 29, said other edge having had a wire *d* placed therein, said wire being 95 backed up and held firmly in place by the flexible mandrel 34. After the sheet has been given the curvature, so as to adapt it to form the cylindrical body of a can or pail, the wired edge *b* constituting the upper 100 edge of such can or pail, the mandrels 34 and *d* are removed so as to leave the curved sheet with its edge which is to form the bottom of the can, open, as shown in Fig. 12. In Figs. 13 and 14 a portion of the cylindrical bottom of the can or pail is indicated at *e*, said bottom having a flange *f* which, of course, in the complete article, will stand 105 vertically. In Figs. 13 and 14, the portions of the parts shown are represented in 110 the positions which they would occupy when the can or pail is lying on one side, this being so represented for the sake of comparison with the figures above, which illustrate the positions occupied by the sheet 115 when passing through the bending machine. After the sheet *a* has been bent, as described, and the mandrels removed, as indicated in Fig. 12, said bottom *e* and its flange *f* is slipped into the annular recess or pocket 120 left by the removal of the mandrels. Before the flange of the bottom is slipped into place, as shown in Fig. 13, the edge of the flange will have been wired in the same manner as the upper edge *b* of the sheet *a*. 125 The wire carried by the edge of the flange *f* may be the same wire which had been used as the mandrel *d*, or it may be another one. After the parts are assembled, as shown in Fig. 13, the can is passed through another 130

machine which simply rolls down the lip *c* to close it tightly upon the wired edge of the flange *f*, as shown at *g* in Fig. 14.

Of course, if the flexible mandrel 34 has not been employed, the roll 35 having been used to support the flange *c* and hold the mandrel *d* crowded into place, then after the sheet has been run through the bending machine, the only thing to remove will be the mandrel *d*, prior to inserting the flange of the bottom *e*. And if a flexible mandrel, such as shown in Fig. 15 is employed, then the only thing to remove will be that one mandrel having the rounded side 34^a.

15 We do not limit ourselves to any particular form of mandrel employed, to support the folded edge of the sheet and the lip *c*, since any member which will prevent any rolling of the flange too far inwardly, and 20 which will prevent bending of the flange in a few places, instead of smoothly and continuously, will suffice.

To carry out our invention, it is, of course, essential that the groove 31 shall be 25 a wide one, and so far as this feature of our invention is concerned, we do not limit ourselves to forming such wired groove in a loose sleeve. And the same is true, of course, in connection with the use of the 30 mandrel, whether the latter be a flexible chain, or not. That is, the operativeness of the machine, so far as the use of the removable mandrel is concerned, is not limited to the feeding rolls being provided with 35 sleeves which are loose, instead of fast, or having integral grooved portions. Preferably, however, the ends of the rolls are free to rotate and to move in the direction of the axis of the feeding portions of the rolls.

40 We claim:

1. The combination with a sheet metal bending machine having a rotary member provided with a groove for the passage of a bent edge of a sheet, of a flexible mandrel 45 to prevent closing in of the lip of the bent edge during curving of the sheet.

2. The combination with a sheet metal bending machine having feeding rolls, and a loosely mounted member in axial alignment with one of said rolls, said member having a peripheral groove for the passage of a bent edge of a sheet, of a flexible mandrel to prevent closing in of the lip of the bent edge during curving of the sheet.

55 3. A sheet metal bending machine having oppositely driven rolls with elongated par-

allel peripheral portions, a lower roll having a loosely mounted peripherally grooved portion at one end, the opposite end of an upper roll having a loosely mounted peripherally grooved portion whereby the machine will bend a sheet having a wired edge projecting in one direction and having its other edge curved in the other direction. 60

4. A sheet metal bending machine having 65 positively driven feeding rolls with elongated parallel peripheral portions, and peripherally grooved loosely mounted members in axial alinement with said rolls, said loosely mounted members being free to 70 move axially relatively to said rolls.

5. In a sheet metal curving machine, a pair of feeding rolls with elongated parallel peripheral portions, a loosely mounted sleeve having a plurality of peripheral 75 grooves and in axial alinement with one end of one of the feeding rolls, the other feeding roll having at the opposite end of the machine a loosely mounted sleeve having a wide peripheral groove. 80

6. A sheet metal curving machine having peripherally grooved rotary members provided with elongated parallel peripheral feeding portions, one of said members consisting of a sleeve having a hub, and a collar adjustably secured on said hub, whereby the width of the groove presented by said member may be adjusted. 85

7. A sheet metal curving machine having a peripherally grooved rotatably mounted 90 member to accommodate a bent edge of a sheet, and a smoothing roll adjacent said rotatably mounted member, said roll having a grooved periphery, to bear on the outer curved surface of the bent edge of the sheet. 95

8. A sheet metal curving machine having feeding rolls, and a loosely mounted peripherally grooved rotary member in alinement with one of the feeding rolls, a bracket having a smoothing roll adjacent said rotary member, said roll having a concave periphery to bear upon the outer surface of the bend of a sheet, and means for holding the material in opposition to the pressure of the smoothing roll. 100

105 In testimony whereof we have affixed our signatures in presence of two witnesses.
